Attorney

UNITED STATES PATENT OFFICE.

DUDLEY J. KAVANAGH, OF BAY CITY, MICHIGAN.

PAPER-FILING DEVICE.

1,330,875.

Specification of Letters Patent. Patented Feb. 17, 1920.

Application filed January 29, 1918. Serial No. 214,336.

To all whom it may concern:

Be it known that I, DUDLEY J. KAVANAGH, a citizen of the United States of America, and resident of Bay City, in the county of 5 Bay and State of Michigan, have invented certain new and useful Improvements in Paper-Filing Devices, of which the following is a specification.

This invention relates to file cases and 10 particularly to a file case having plaits or folds, the folded portions or some of them being punctured or perforated for the reception of eyelets or the like, whereby papers are held in the case, although the said invention may also be employed as a container 15 to be placed in a file case.

An object of this invention is to provide a collapsible file case or extensible file case; that is to say, the file case is compact and the 20 folds thereof allowed to be collapsed when not in use, whereas the case may be extended or distended for increasing its capacity as the papers are filed and accumulate.

A further object of this invention is to 25 prevent the loss of papers by producing a file in which the papers can be bound and secured, either temporarily or permanently as will presently appear.

With the foregoing and other objects in 30 view, the invention consists in the details of construction, and in the arrangement and combination of parts to be hereinafter more fully set forth and claimed.

In describing the invention in detail, reference will be had to the accompanying 35 drawings forming part of this specification, wherein like characters denote corresponding parts in the several views, and in which—

40 Figure 1 illustrates a view in perspective of a file case embodying the invention;

Fig. 2 illustrates a sectional view of a fragment of the file showing the manner of using the file;

45 Fig. 3 illustrates a sectional view of a modified construction showing fasteners applied to the case; and

50 Fig. 4 illustrates a plan view of a fragment of a case showing the temporary attachment.

In these drawings 5 denotes the top of the container or jacket, 6 the bottom thereof, and 7 a wall having a fold or crease 8 so that one portion of the wall will move with 55 relation to the other to increase or diminish the height of the wall according to the

papers contained within the jacket or receptacle.

The wall or end 9 is accordion plaited with the upper layers or folds 10 provided 60 with perforations or holes 11 for the reception of eyelets whereas the lower fold 12 is preferably plain, although, as will presently appear, these lower folds may have slots in them.

In the construction of the container, relatively stiff papers or cloth or cloth reinforced paper may be employed and any number of folds or plaits may be provided and preferably in use, papers to be filed are 70 placed in an unfolded state with their upper edges in the folds of the accordion plaited wall and fastened by staples or eyelets 13 which pass through the apertures 11. The apertures 11 are intended to receive eyelets 75 or fastenings by which papers may be secured in place, and these fastenings or eyelets may be inserted in the apertures and through the papers to be filed.

If desired, the papers thus placed in the 80 file or jacket may be placed in a file, envelop or container of known construction, or if desired, a flap could be extended under the back and around the open side and over the top of the receptacle or file, and thus the 85 device could be made a complete closure for protecting papers which it contains.

In the modification shown in Figs. 3 and 4, there is a plurality of folds or plaits such as 14 and means for locking papers in the 90 holder temporarily may be provided instead of supplying the fastening which is embodied in Fig. 2. This modification consists of the jacket or holder of the construction heretofore described, but in addition 95 to the holes 11 on the upper fold to apply the fastenings, the papers are fastened to the lower folds 15 by means of a fastener having a button 16 which is first fastened to the top of the paper to be filed, and then 100 inserted in the slot 17 cut with a die or the like in the lower fold, thus provision may be made for changing the papers or adding to them by using the temporary fastenings and afterward the fastenings may be employed which pass through the papers and other apertures 11.

The slotted portion has oppositely recessed edges 18' and 19 forming a clearance for receiving heads of paper fastening devices 16 the paper being held thereby being identified by the reference numeral 20,

After the heads of the paper fasteners are inserted in the recessed portions of the slotted portions of the file, they are slid longitudinally of the slot in order that said heads may not disengage.

5 The folded file has a series of apertures *a* through which a securing device 18 is threaded, which securing device may be elastic or other flexible elements and is intended to prevent flaring of the file, notwithstanding it may contain a number of papers.

10 I claim—

15 1. In a paper filing device, a receptacle having one end folded and the opposite end provided with accordion plaits, the upper fold of each plait being apertured for the

reception of fasteners by which papers are held in the holder.

2. In a paper filing device, a receptacle 20 having an accordion plaited wall at one edge and a folded wall at the opposite edge, one of said folds of the plaits being slotted, and fastenings adapted to be attached to papers to be filed and inserted in said slots.

25 3. In a paper filing device, a receptacle having on accordion plaited wall at one end, the upper folds being apertured for the reception of temporary paper fasteners and the lower folds being slotted and recessed to receive the heads of paper fasteners, the shanks of the paper fasteners being 30 slidable in the slots.
